ALKYLATION OF HYDROCARBONS

Louis A. Clarke, Fishkill, N. Y., assignor to The Texas Company, New York, N. Y., a corporation of Delaware

Application December 24, 1942, Serial No. 470,043

9 Claims. (Cl. 260—683.4)

1

This invention relates to alkylation for the production of motor fuel hydrocarbons of high antiknock value, and more particularly to the alkylation of paraffin hydrocarbons with olefins or other suitable alkylating agents in the presence of a liquid alkylation catalyst.

One of the principal objects of the invention is to provide an improved method of carrying out this alkylation reaction to obtain large yields of high quality alkylate with good catalyst life while avoiding emulsion and settling difficulties, eliminating or minimizing corrosion difficulties and effecting economy in power consumption.

Still another object of the invention is to provide novel and improved apparatus for carrying out this alkylation reaction and accomplishing the above noted advantages, the apparatus being simple in construction and of low initial and maintenance cost.

Other objects and advantages of the invention will be apparent from the following description when taken in conjunction with the accompanying drawings and appended claims.

Heretofore, alkylation of an isoparaffin with an olefin has been carried out commercially in several different types of equipment or reactors. One generally used type is the so-called pump and time tank reactor wherein the feed hydrocarbons are introduced at the suction side of a pump into an emulsion recycle stream of mixed catalyst and hydrocarbon, the stream being forced with turbulent flow through a suitable chiller and then into a time tank which usually contains suitable baffles or other means for preventing breaking of the emulsion. A substantial proportion of the stream withdrawn from the time tank is recycled to the recirculating pump while a minor proportion is withdrawn for recovery of alkylate. While this type of equipment functions very satisfactorily with certain catalysts, particularly sulfuric acid, difficulties are encountered when it is attempted to adapt that equipment to a liquid catalyst containing suspended solid material, such as an aluminum halide-hydrocarbon complex containing added aluminum halide, due to clogging of the lines and other causes. Moreover, the power requirements for operating the pump are material; and corrosion difficulties of the moving parts of the pump, the pump packing and other parts are experienced with certain highly corrosive catalysts, such as hydrofluoric acid.

Another type of equipment which has been used commercially for alkylation and operates upon this general principle of emulsion recycle

2

is the so-called mixer of the turbo type which utilizes internal recirculation of emulsion at very high velocity. The power requirements for this type of apparatus are substantial, and other objections and difficulties with certain types of catalysts, as noted above, are encountered.

A third type of apparatus which has been used commercially for this alkylation reaction is the so-called jet reactor wherein the hydrocarbon and catalyst are pumped under high pressure and introduced through a jet or thimble having a plurality of ports into the catalyst-hydrocarbon mixture so as to produce substantial agitation and emulsification of the contents of the reactor. In this form, emulsion is withdrawn through an overflow, a minor portion being passed to a suitable settler, and a major portion of the emulsion being recycled to the jet. This type of equipment retains all the disadvantages noted above.

20 The present invention provides a novel reactor which is generally applicable to the various types of liquid alkylation catalysts. The expression "liquid alkylation catalyst" is used throughout the description and claims to mean a material 25 which is fluid and pumpable even though it may contain dissolved or suspended solids or gases. This includes among others a pure liquid such as anhydrous hydrofluoric acid, a liquid containing dissolved gas or other liquid such as hydrofluoric acid containing dissolved boron fluoride, and a liquid containing finely divided suspended matter 30 but which is fluid and pumpable, such as aluminum halide-hydrocarbon complex containing suspended aluminum halide. Moreover, by means 35 of the novel method of this invention, emulsion and settling difficulties are avoided, corrosion and erosion of parts, such as pumps and pump packings, are effectively eliminated, and economy may be effected in power consumption.

40 In accordance with the present invention, the liquid alkylation catalyst is maintained as a relatively stationary body in the continuous phase in a vertical reactor of substantial height, such as a tower, and a mixed feed of paraffin hydrocarbon and olefin or other alkylating agent in liquid phase, with the paraffin in substantial molar excess of the alkylating agent, is introduced through a small orifice or a plurality of orifices into the lower portion of the liquid catalyst body. As a matter of convenience, the invention is described hereinafter in connection with the use of olefin as the alkylating agent, but it is to be understood that other alkylating agents can be used in place of the olefin, as more particularly pointed out hereinbelow. The mixed

feed passes through the orifice or orifices in such a manner that the feed liquid is dispersed in fine drops in the continuous catalyst phase.

The liquid alkylation catalyst has a higher specific gravity than the mixed paraffin hydrocarbon and olefin employed, whereby the dispersed drops of hydrocarbon mixture rise upwardly through the body of liquid catalyst due to this difference in gravity. While there is some turbulence of the liquid catalyst body adjacent the point or points of introduction of the hydrocarbon mixture, there is insufficient agitation to form an emulsion. By the expression "emulsion" is meant the intimate mixture of subdivided particles of both catalyst and hydrocarbon heretofore produced in alkylation reactions of this character by mechanically driven stirrers, high capacity pumps producing turbulent flow, or agitating jets which produce efficient mixing and movement of the catalyst along with the hydrocarbon through the reaction zone. Such an emulsion resists breaking in the reaction zone or reactor and is passed from the reactor into a relatively quiescent zone of a settler, where sufficient settling time is allowed for separate catalyst and hydrocarbon phases to be formed. In the present case, the hydrocarbon mix passes into the maintained body of catalyst liquid in the form of dispersed drops without emulsification. Even though there may be a localized disturbance of the lower portion of the continuous catalyst phase due to the higher velocity of the hydrocarbon adjacent the locus of introduction, the liquid catalyst remains as a continuous phase. The dispersed drops of hydrocarbon rise upwardly through the tower without corresponding upward movement of the catalyst liquid. The net result is that the hydrocarbon mix passes in dispersed form upwardly through a relatively stationary continuous catalyst phase, and promptly forms a separate and superposed hydrocarbon layer as it reaches the top or upper surface of the catalyst liquid.

As distinguished from the prior practice in this art, wherein highly efficient agitation with the formation of emulsion was considered a prime requisite for the production of high yields of alkylate of good quality, it has now been discovered that such emulsion-forming agitation can be avoided while still obtaining the desired results by utilizing the principles of the present invention. As stated above, the liquid catalyst is relatively unagitated except for such turbulence and liquid flow as results from the introduction of the reactants, and the movement of the dispersed drops of reactants upwardly through the maintained body of catalyst liquid. There is substantially unidirectional flow of the hydrocarbon or reactant phase upwardly through the relatively stationary continuous catalyst phase. Also, the orifice is of such small size, generally having a diameter of about $\frac{1}{2}$ inch to $\frac{1}{2}$ inch, and is so correlated with the through-put, that the hydrocarbon reactants are dispersed in the form of small drops of various sizes not exceeding about $\frac{1}{4}$ inch in diameter, and preferably much smaller so as to have a large surface area to volume ratio. This affords a large area of contact between the outer film of each drop and the surrounding catalyst liquid. This operation has been found to promote the desired alkylation reaction between the paraffin and the olefin present in the dispersed drops as the latter pass upwardly through the substantial height of continuous catalyst phase.

As the drops of mixed alkylate and unreacted hydrocarbon reach the upper surface of the cata-

lyst body, they coalesce to form a superposed hydrocarbon layer. A distinct interface between the liquid catalyst body and the superposed hydrocarbon layer is generally maintained in the upper portion of the tower. A stream of this hydrocarbon layer overflows through a discharge line in accordance with the feed rate to the tower.

It is found with some catalysts that the dispersed hydrocarbon drops may tend to entrap a small amount of the catalyst liquid in this superposed hydrocarbon layer. Since the rate of rise of the dispersed drops of hydrocarbon through the catalyst is relatively slow, a considerable volume of dispersed hydrocarbon is normally present at any one time in the catalyst liquid, so that the interface level in the tower during operation is substantially above the initial level of the catalyst alone. Moreover, accidental or deliberate fluctuations in the throughput may cause the interface level to vary; and increase in throughput may cause the level to reach the point of stream withdrawal. Further, the tower can be satisfactorily operated with the interface level at the stream withdrawal point so that the catalyst continuously overflows along with hydrocarbon. In order to insure that catalyst thus carried over with hydrocarbon does not pass into the neutralizing and fractionating sections of the unit, a separator or trap is provided adjacent the point of stream withdrawal and preferably at about the level thereof. Since such catalyst as is entrapped in the superposed hydrocarbon layer or overflows through the stream withdrawal is not in the form of an emulsion with the hydrocarbon, it immediately, or at least rapidly, drops out in this separator, so that large settling volume with substantial settling time is not required as in the case of an emulsion. However, the trap or separator can be constructed of substantial volume, when hydrocarbon recycle is employed, to function as a reservoir for the circulating hydrocarbon. All or any portion of this trapped-out catalyst is preferably returned to the maintained catalyst body within the tower, together with such make-up catalyst as may be required. In continuous operation, a portion of this catalyst may be intermittently or continuously discharged from the system to recovery, and fresh catalyst introduced to make up for that withdrawn.

The recycle of settled hydrocarbon unmixed with acid or other catalyst to the alkylation reaction zone has heretofore been proposed in connection with reactors operating with efficient agitation and the formation of emulsions. However, this requires very extensive settling volume, particularly where the recycle rate is many times the fresh feed rate. Consequently, such hydrocarbon recycle has not proved commercially attractive, and emulsion recycle has been universally employed. While a once-through operation is feasible in the present reactor, it is found that materially improved results can be secured in many cases by recycling hydrocarbon to the reaction zone. Preferably a high recycle ratio of the order of about 10 to 50 volumes or more of hydrocarbon recycle to 1 volume of fresh feed is employed. This materially increases the ratio of paraffin to olefin in the reaction zone and increases the effective time of contact, as is well known. Since the settling is quite rapid or almost instantaneous in the present operation, it is apparent that the difficulties inherent in previous proposals involving recycle of hydrocarbon separated from an emulsion are effectively over-

come. The recycled hydrocarbon is preferably first admixed with the fresh feed hydrocarbon, and the mixture introduced through the orifice or orifices into the reaction zone. The trapped-out catalyst is preferably returned directly and by gravity to the maintained catalyst body, thereby avoiding the use of pumps in the handling of the more corrosive catalyst liquid.

If desired, the reactor or tower of the present invention may be supplied in the reaction zone with one or more layers of solid contact or filling material to thereby increase the length of the path of flow and the time of contact for each once-through flow of the dispersed drops in the catalyst liquid. The packed tower can be operated with once-through flow or hydrocarbon recycle. Any suitable contact material, which is non-reactive with respect to the catalyst and the reactants and which provides sufficient free space for the proper travel of the drops, may be employed. A very suitable type of material for this purpose consists of small contact pieces, each shaped to simulate a saddle, and known to the trade as "berl saddles". There is some indication that the use of a packing in the tower may enable the use of somewhat larger size drops and obtain as good results as with a higher degree of dispersion (i. e., smaller size drops) in an unpacked tower. Moreover, the combination of a packed tower with a high degree of dispersion can be used. However, very satisfactory results are secured with an unpacked tower operating with either once-through flow or hydrocarbon recycle, preferably the latter.

Any of the conventional catalytic alkylation reactions can be carried out by the method and with the apparatus of the present invention. Thus, the reaction of an isoparaffin with an olefin or other alkylating agent, as well as the alkylation of a normal paraffin with an olefin or other alkylating agent, in the presence of suitable alkylation catalysts can be accomplished. The paraffin charge stock may be either normally gaseous or normally liquid or a mixture thereof. In isoparaffin alkylation, isobutane and isopentane are preferred, although it is to be understood that any of the low boiling isoparaffins may be used and conventional catalysts effective for such isoparaffin alkylation can be employed. The present invention appears particularly effective for isoparaffin alkylation with hydrofluoric acid or aluminum chloride-hydrocarbon complex containing suspended aluminum chloride as the catalyst. Likewise normal paraffins can be alkylated with olefins or other alkylating agents in the presence of suitable catalysts, such as hydrogen fluoride containing dissolved boron trifluoride or aluminum chloride-hydrocarbon complex containing suspended aluminum chloride. Various normally gaseous or liquid normal paraffins, such as normal butane, normal pentane and higher normal paraffins or mixtures thereof, may be used for the charge stock. Likewise, mixtures of isoparaffins and normal paraffins may be employed. The features of tower type alkylation of the present character, as applied to isobutane-ethylene with an activated aluminum chloride-hydrocarbon complex catalyst, is disclosed and claimed in the copending application of Louis A. Clarke, Serial No. 535,261, filed May 12, 1944.

The olefin charge stock may be any of the normally gaseous or normally liquid olefins or mixtures thereof. For example, ethylene, propylene, butylenes, amylenes, C₄ polymers such as di-isobutylene and tri-isobutylene, cross poly-

mers of isobutylene and normal butylene, mixed or non-selective C₃-C₄ polymers, and the like, and various fractions of thermally or catalytically cracked gasolines and of polymer naphthas may be used.

In place of an olefin as the alkylating agent, various alcohols and ethers, such as isopropyl alcohol, tertiary butyl alcohol, secondary butyl alcohol, isopropyl ether and the like, may be employed with suitable known alkylation catalysts which have tolerance for water liberated in the reaction. Likewise, the corresponding alkyl esters, such as the alkyl halides, sulfates, phosphates, etc. of the olefins, may be used as the alkylating agent with an appropriate or compatible alkylation catalyst, as is well known. Wherever the expression "alkylating agent" is used throughout the description and claims, it will be understood that this refers to olefins as well as alcohols, ethers and esters of the character described above and which are capable of reacting with a paraffin or other hydrocarbon having a replaceable hydrogen atom to produce an alkylated hydrocarbon of higher molecular weight of the character set forth herein.

Any of the well known conditions suitable for the various alkylation reactions can be used. In general, a substantial molar excess of paraffin to olefin or other alkylating agent is employed, such as a feed ratio in excess of 1:1 and preferably about 4:1 to 8:1, which provides a substantially higher contact ratio in the reaction zone generally in excess of about 50:1 when hydrocarbon recycle is used. The reactor is maintained under sufficient pressure to insure that the hydrocarbons and alkylating agents are in the liquid phase. The temperature of the reaction varies with the hydrocarbons or alkylating agents employed and with the catalyst, as is well understood, but generally ranges from about -40° F. to about 150° F. A high ratio of catalyst to hydrocarbon is inherently maintained in the reaction zone due to the maintained body of catalyst liquid of substantial height through which the hydrocarbon phase is dispersed. As pointed out above, the present invention departs radically from the previous practice in this art with respect to agitation, since mechanical stirrers and high capacity pumps with efficient agitation are avoided, and introduction of dispersed hydrocarbon without the formation of an emulsion and the rising of hydrocarbon drops through the relatively stationary body of continuous catalyst phase by the difference in gravity therebetween, are substituted.

The invention is more particularly illustrated in the attached drawings which disclose preferred embodiments thereof. In the drawings:

Fig. 1 is a diagrammatic illustration of apparatus suitable for carrying out the method of the present invention;

Fig. 2 is a partial vertical sectional view on an enlarged scale of the tower reactor of Fig. 1.

Fig. 3 is a partial view similar to Fig. 2 of a modification;

Fig. 4 is a plan view of the orifice plate of Fig. 3; and

Fig. 5 is a partial view similar to Fig. 2 of a second modification.

Referring to the drawings, particularly Fig. 1, the hydrocarbon mix containing the paraffin and olefin in liquid phase is introduced by pump 9 through pipe 10 controlled by valve 11 into the bottom of tower 12 beneath the orifice plate 13. The tower may be equipped with an external

jacket 15 provided with inlet 16 and outlet 17 for the supply of a suitable cooling or heating medium to maintain the desired temperature within the reaction zone. It is to be understood that other conventional means for controlling the temperature in the reaction zone can be used, such as the fresh feed and recycle hydrocarbon chiller hereinafter described, internal evaporative cooling, etc. As shown more particularly in Fig. 2, the tower is partially filled with a suitable liquid catalyst 18. The amount of catalyst liquid is generally such that, during operation with an appreciable volume of hydrocarbon liquid dispersed in the catalyst at any one time, the interface 19 between the relatively stationary body of liquid catalyst and the superposed hydrocarbon layer 20 is positioned adjacent the upper end of the tower.

The orifice plate 13 is provided with an opening or orifice 22 shown as positioned at the vertical axis of the tower, this orifice being of small size of the order previously indicated. The entire tower is maintained under sufficient pressure so that the hydrocarbon mix supplied by line 10 is in liquid phase, and this mix is under sufficient additional pressure to counter-balance the height of the liquid column within the tower and to overcome the pressure drop through orifice 22 to obtain the desired dispersion. The space 23 in the tower beneath the orifice plate 13 remains filled with the hydrocarbon mix, and the catalyst liquid is prevented from flowing down through the orifice into this space and backing up into the inlet pipe 10 by the maintained feed pressure. This causes the hydrocarbon to pass through orifice 22 with the formation of a multitude of small drops indicated at 24, which pass up through the liquid catalyst body due to the difference in gravity between the catalyst and the hydrocarbon. As the drops reach the interface 19, they coalesce to form the superposed hydrocarbon layer 20.

While the orifice plate 13 can be equipped with a simple opening in some cases, it is preferably provided with an upstanding nozzle 25 of a known type adapted to effect a spray dispersion of the hydrocarbon in the form of fine drops. For any given nozzle of this character, at the lower throughput or rate of supply of hydrocarbon, fewer drops of a larger size will issue from the opening or discharge orifice of the nozzle. Theoretically, the throughput rate can be reduced to the point where the drops issue one after the other in relatively slow succession, provided the orifice is sufficiently small so that each individual drop is of a proper small size. As the throughput rate is increased from this given orifice, the drops not only issue faster but are of smaller size. This also causes the level of the interface 19 to rise, due to the larger number of dispersed drops and the greater volume of hydrocarbon present in the liquid catalyst body at any one time. As the throughput is further increased, the drops become exceedingly fine and the interface level reaches a maximum height. Further increase of the throughput beyond this limit causes an accumulation of hydrocarbon to be formed within the base of the tower surrounding the nozzle, from which globs of the hydrocarbon break off and rise upwardly through the tower. This latter condition results in a drop in the interface level, due to the fact that the degree of dispersion and the quantity of hydrocarbon dispersed in the catalyst liquid at any one time is then reduced. Consequently, this last

mentioned condition of operation, which is objectionable and is to be avoided, can be readily detected by the drop in interface level. While satisfactory operation can be secured at the lower throughputs described above, it is generally desirable to operate in the upper portion of the throughput range which produces greater dispersion and a higher interface level approaching the upper limit described above.

Referring again to Fig. 1, the tower 12 is equipped with an overflow or outlet 26 through which the hydrocarbon layer 20 is discharged in a stream to a suitable separator or trap 27. As shown, this is preferably a cylindrical vessel arranged with its longitudinal axis somewhat inclined to the horizontal. Adjacent the lower end of the separator, a bottom discharge line 28 is provided to conduct catalyst by gravity back to the lower portion of the tower. Pipe 28 opens into the tower at a locus 29 opposite the maintained catalyst body 18, so that this catalyst is returned directly thereto.

The upper end of separator 27 is also provided with an overflow 30 connected with branched lines 31 and 32 controlled by valves 31' and 32' respectively. Hydrocarbon may be passed to the alkylate discharge line 31 or a portion of the alkylate passed to the discharge line 31 and the balance to the hydrocarbon recycle line 32 containing a suitable pump 33. Line 32 communicates with the hydrocarbon mix feed line 10, a suitable surge drum 34 being preferably connected to line 32 by branch line 34' in advance of pipe 10 to take care of fluctuations in the pumping rate and to maintain the regulated pressure in the feed line 10. Preferably, a suitable chiller or heat exchanger 35 is positioned within line 10 in advance of the tower inlet to precondition the temperature of the fresh feed hydrocarbon and the recycle hydrocarbon to maintain the desired temperature within the reaction zone of the tower. Any suitable control means can be used for regulating the pressure and rate of through-put of the fresh feed and hydrocarbon recycle through the orifice to thereby control and regulate the degree of dispersion of the drops in the catalyst liquid, such as the proportioning pumps 9 and 33 and the surge tank 34 as shown.

As pointed out above, a major portion of the hydrocarbon is preferably recycled through line 32 and re-introduced together with the fresh feed through line 10 into the tower. A minor proportion of the settled hydrocarbon is withdrawn in accordance with the fresh feed rate through pipe 31 and passed by pump 36 together with suitable neutralizing agent, such as caustic soda solution, introduced by line 37, into a scrubber 38 where the hydrocarbon is neutralized. The neutralized material overflows by line 39 into an intermediate portion of a settler 40 where the caustic soda solution settles out and is withdrawn through line 41. The bulk of the solution is recycled by line 42 to line 37 for reuse in treating fresh quantities of hydrocarbon, while a minor proportion may be withdrawn intermittently or continuously by a discharge line 43, fresh make-up caustic soda solution being added by feed line 44.

The neutralized and settled hydrocarbon overflows from settler 40 through line 45 and is introduced by pump 47 into a stabilizer 48 where unreacted gases including excess paraffin are removed overhead by line 49. These lighter gases are forced by pump 50 into a suitable frac-

tionator 51 where separation is made between unreacted isoparaffin, such as isobutane, which is withdrawn by overhead line 52 for recycling to the reaction tower 12, and any heavier hydrocarbons such as normal butane, which are withdrawn by bottom line 53. It will be understood that the fractionating system shown is that particularly designed for isobutane alkylation wherein the charge, which may be a suitable refinery C₄ cut, also contains normal butane. However, the fractionating system can be modified from that shown in accordance with the charge stock being handled as is well understood in the art.

The stabilized alkylate is removed from the bottom of stabilizer 48 by line 55 and passed by pump 56 to a suitable fractionator 57 which serves to take overhead a desired fraction, such as an aviation fraction boiling up to about 350 to 375° F. A heavier residue fraction is removed by bottom discharge line 58. The overhead vaporized fraction passes by line 59 through a suitable condenser 60, and the condensed liquid flows by line 61 into an accumulator 62. Any light gases may be bled off from accumulator 62 by vapor drawoff 63 and the desired stabilized fraction of the alkylate is removed by bottom line 64 to suitable blending tanks or storage (not shown).

The reaction tower 12 illustrated in Fig. 2 is of a relatively smaller capacity type having a single orifice 22. This tower may be conveniently constructed of an interior diameter of about one inch to 12 inches or more, with an orifice selected to give fine dispersion and a lateral distribution to substantially extend throughout the cross-section thereof. The tower may be from about 5 feet to 20 feet or more in height. It will be understood that this is merely representative of satisfactory tower reactors having a single orifice, and that the invention is not limited to towers of these dimensions. However, for a single orifice type, the height should be many times greater than the diameter. Such towers have been successfully operated with heights of catalyst liquid varying from about 30 inches up to about 200 inches or more.

Where a plural number of orifices are used, the diameter of the tower may be greatly increased without necessarily increasing the height. The latter dimension is regulated in accordance with the charge stocks and catalysts with a view to insuring substantially complete disappearance of the olefin or other alkylating agent as such in a once-through passage. Objectionable side reactions due to prolonged contact of hydrocarbon or unreacted olefin with catalyst in transfer lines and settlers are minimized or avoided. It is to be understood that two or more towers can be used with series flow of hydrocarbon therethrough, where the desired degree of conversion or reaction cannot be accomplished in a single tower of practical height. In this tower reactor, the time of contact for all portions of the reacting hydrocarbons is uniform.

In Figures 3 and 4, there is shown a modification of the tower reactor particularly designed for larger scale operation. In this form the tower 70 is of relatively larger diameter, such as from two to six feet or more. A bottom orifice plate 72 is provided with a plurality of upstanding nozzles 73 arranged more or less uniformly over the cross section of the plate. Each nozzle is constructed to provide effective dispersion in the manner previously described, the several nozzles being so

spaced as to substantially encompass the cross-section of the tower with the drops. This produces a series of sprays of drops 75 into the lower portion of the maintained liquid catalyst body, while avoiding undue agitation, and avoiding undue interference of the drops from one nozzle with those from another.

Figure 5 discloses another modification wherein the tower 80 is provided with a packing 81 of solid contact material above the orifice plate 82. While a nozzle or plurality of nozzles can be used in this form, it is found that with certain catalysts such as an aluminum chloride-hydrocarbon complex containing suspended aluminum chloride a simple opening or orifice 83 through the orifice plate functions satisfactorily to accomplish the desired dispersion and distribution of the hydrocarbon drops throughout the catalyst liquid, as aided by the contact material. This packing may extend throughout substantially all of the contact zone containing the liquid catalyst, or may extend above the orifice plate 82 throughout only a portion of the height of the tower confining the catalyst, with an upper unpacked section 84. As shown, the hydrocarbon issuing from orifice 83 in the form of the dispersed drops 85 is distributed within a short upward travel throughout the cross-section of the tower. The dispersed drops rise through the catalyst liquid through the free space provided by the packing, the latter impeding the normal velocity of upward travel due to difference in gravity and increasing the length of the path of travel thereof.

While a nozzle, or a plurality of nozzles, adapted to direct the drops upwardly within the tower, has been shown in the drawings, it is to be understood that this arrangement is not essential. Thus, the nozzle may be directed in an inclined or horizontal direction, so long as the hydrocarbon is dispersed into the catalyst liquid in the form of fine drops as described above, which are then free to rise through the catalyst liquid, and so long as undue agitation and emulsification are avoided. Moreover, it is to be understood that other types of dispersing devices can be employed, such as a cone adapted to introduce the hydrocarbon from the periphery thereof and thus disseminate the drops over a larger area of the cross-section of the tower.

The invention is further illustrated by the following specific examples; but it is to be understood that these are given by way of explanation and the invention is not limited thereto.

Example I

The following example illustrates the application of the invention to the alkylation of a mixture of isobutane with a C₄ fraction from a cracking operation, using anhydrous HF as the catalyst. The mixed hydrocarbon charge had the following analysis:

	Weight percent
Propane	1.4
Isobutane	68.6
Normal butane	14.7
Isobutylene	6.9
Normal butylenes	8.0
C ₅	0.4

The apparatus employed in the following runs included a tower constructed of one-inch steel tubing about seven feet long equipped with a jacket through which cooling water was passed for the purpose of controlling the temperature. The overflow from the tower was connected with an inclined separator made of copper which was

two inches in diameter by seven feet long. The tower was operated under two conditions, namely, packed for about five feet of its height with brass-plated steel jack chain and utilizing once-through operation for one continuous run, and unpacked with top separator recycle for a second continuous run. The volumetric characteristics of the tower were as follows:

	cc.
Volume of tower unpacked	1340
Free space in tower packed	1050
Free space in tower to top of packing	675

The tower was provided with an axially-arranged orifice $\frac{3}{2}$ inch in diameter.

In the run with the packed tower, the latter was charged with 605 grams (605 cc.) of anhydrous liquid HF which nearly filled the packed portion thereof. The remainder of the system was then filled with isobutane, and the premixed charge, composed of a primary debutanizer overhead and commercial isobutane which had the above listed analysis, was charged into the bottom of the maintained catalyst body through the orifice at a charge rate varying from 0.4 to 1.6 pounds per hour. The hydrocarbon mixture passed upwardly through the packed catalyst layer, and a stream of the superposed hydrocarbon layer was continuously withdrawn to the separator, from which a top effluent hydrocarbon stream was passed through a caustic scrubber, stabilized, distilled and tested.

In the run with the unpacked tower employing top separator recycle, the tower was charged with 415 grams (415 cc.) of the anhydrous liquid HF and the free space filled with isobutane. Hydrocarbon fresh feed of the same composition together with hydrocarbon recycle from the top of the settler were passed through the orifice into the catalyst body, the fresh feed charge rate being 0.4 pound per hour and the recycle rate being 1.7 gallons per hour. A stream from the hydrocarbon layer in the tower was passed to the separator, from which a major portion of the hydrocarbon was recycled to the fresh feed inlet while the remainder was passed through a caustic scrubber, stabilized, distilled and tested.

Each of the runs was continued for a period in excess of about 50 hours. The conditions and results of the runs were as follows:

	Packed tower single pass	Unpacked tower-top separator recycle
Charge rate, pounds per hour	0.4-1.6	0.4
Recycle rate, gallons per hour	None	1.7
Temperature, ° F.	70	70
Isobutane/olefin mol ratio	5:1	5:1
Yield debutanized alkylate		
Weight per cent on olefin	184	182
Volume per cent 311° F. E. P. fraction on basis of total debutanized alkylate	77	90
Volume per cent 2,2,4 trimethylpentane on basis of total debutanized alkylate	20	48

Octane number of 311° F. E. P. alkylate	AFD-1C	CFRM
Clear	90.6	94.6
Plus 1 cc. TEL/gallon	97.1	Iso-octane+1.26 cc. TEL
Plus 3 cc. TEL/gallon	Iso-octane+0.14 cc. TEL	
Plus 6 cc. TEL/gallon		Iso-octane+1.98 cc. TEL

It was found in this work that the method and

apparatus of the present invention avoided hydrogen transfer reaction with the production of n-butane in the above noted C₄ alkylation with HF. An analysis of the offgas from the run with the unpacked tower listed above showed the following:

	Weight per cent
Propane	1.3
Isobutane	75.7
Normal butane	21.6
Residue	1.4

Calculating from the charge stock employed and assuming no hydrogen transfer reaction, the theoretical weight percentage of normal butane in the offgas should be 21.5%. It is thus seen that alkylation took place in the presence of HF under these conditions without this objectionable side reaction, thereby avoiding the formation of undesired normal butane.

Example II

The following runs illustrate the alkylation of a normal paraffin, such as normal butane, with an olefin in the presence of a catalyst containing a major proportion by weight of anhydrous liquid HF and a minor proportion of BF₃ dissolved therein, under the general conditions set forth in the copending application of Louis A. Clarke, Serial No. 438,418, filed April 10, 1942. Briefly, these conditions include a high normal paraffin-to-olefin mol ratio, a catalyst consisting of HF containing less than 46% by weight of BF₃ based on the weight of the mixed catalyst and generally about 12-20%, a temperature within the range of 0-150° F. with about 70-130° F. being preferred, a pressure of about 100-250 pounds per square inch, and a high catalyst to hydrocarbon ratio in the reaction zone. As set forth in the said copending application noted immediately above, this reaction not only effects alkylation of normal paraffin with olefin but concomitantly effects isomerization or the production of a substantial yield of isobutane.

A series of continuous runs utilizing the HF-BF₃ catalyst for the alkylation of normal butane with various olefins to produce alkylate and concomitantly form isobutane were carried out in accordance with the present invention in a stainless steel unpacked tower eight feet high and one inch inside diameter. The catalyst is highly corrosive to iron and ordinary steel; but copper, Monel metal and 18-8 stainless steel satisfactorily resist corrosion. A convenient method of maintaining the required amount of BF₃ in the catalyst liquid, which was used in these runs, involves saturating normal butane at room temperature and about 160 pounds per square inch pressure with BF₃; and introducing this normal butane saturated with BF₃ together with a stream of mixed normal butane and olefin through the orifice at the bottom of the tower into the previously supplied catalyst liquid. The tower was provided with a $\frac{1}{8}$ inch diameter orifice. A brass tube two inches in diameter and seven feet long served as a separator.

In starting up the run, the system was filled to 200 pounds pressure with catalyst and normal butane. Various heights of the maintained body of catalyst were employed in different runs; but in the runs listed below, a height of about 108-109" was used with very satisfactory results. Top separator recycle was employed, and catalyst was returned to the tower by gravity flow. The portion of the hydrocarbon not recycled was caustic neutralized, stabilized, fractionated and tested.

The following are the conditions and results on two continuous runs of extended duration on normal butane-propylene and normal butane-ethylene respectively:

Olefin	Propylene	Ethylene
Catalyst height inches	109	108
Temperature, ° F.	70	70
Charge rate, pounds per hour	0.8	0.8
Recycle/charge volume ratio	23.3	23.3
Butane/olefin mol ratio	7.9	10.5
Stabilized alkylate: Yield per cent by weight basis olefin	257	394
311° F. E. P. fraction per cent by volume of stabilized alkylate	95.6	96.1
Bromine number	0	0
Octane number CFRM		83.9
Residue per cent by volume of total alkylate	4.4	3.9
Bromine number		2
Volumes of alkylate per volume of catalyst	12.2+	29.2+
Isobutane:		
Weight per cent yield basis normal butane	27.1	40.4
Weight per cent yield basis olefin	292	420
Weight per cent yield basis catalyst	974	1,988

In the series of runs mentioned above, it was found that by increasing the height of the catalyst from 31" to 109" in normal butane-propylene alkylation employing hydrocarbon recycle, there was an increase in the yield of alkylate basis olefin, the percent of alkylate boiling below 311° F., the conversion of normal butane to isobutane and the catalyst life. Also, by increasing the ratio of top settler recycle to fresh feed from 11.7 to 23.3, the yields and catalyst life were improved. Higher yields of alkylate and isobutane based on the olefin charged were obtained from normal butane-ethylene alkylation than from normal butane-propylene alkylation.

While the invention has been described above in connection with the alkylation of paraffins with olefins or other alkylating agents, it is also contemplated that the method and apparatus of the present invention can be employed for the alkylation of other hydrocarbons having a replaceable hydrogen atom, such as aromatic and naphthene hydrocarbons, with olefins or other alkylating agents, such as alcohols, ethers and esters. For example, the alkylation of benzene with propylene for the production of isopropyl benzene, the alkylation of benzene with ethylene for the production of ethyl benzene, etc., in the presence of suitable well known liquid catalysts which are immiscible with the hydrocarbon reactants, can be carried out in the manner and with the tower reactor as described above.

While in certain cases, the same liquid catalyst body as originally supplied to the tower may be maintained therein for the entire reaction, thus providing continuous feed of hydrocarbon with batch feed of catalyst, it is to be understood that a portion of the liquid catalyst may be continuously or intermittently withdrawn and replaced with fresh catalyst during continuance of the process. By the expression "relatively stationary" as applied to the liquid catalyst body, it will be apparent that this signifies that the hydrocarbon moves relatively to the catalyst body and at a substantially greater rate or velocity, irrespective of such localized movement or turbulence which may exist within the catalyst liquid, particularly at the lower portion thereof. Moreover, it is to be understood that this expression includes operations in which a small portion of the catalyst liquid may continuously or intermittently overflow to the separator and be returned through the gravity line or in other suitable manner to the liquid catalyst confined within the tower, as well as an operation in which a portion of the

catalyst liquid may be continuously or intermittently withdrawn from a lower or intermediate portion of the tower, and fresh catalyst liquid supplied to the maintained catalyst body continuously or intermittently at an upper or intermediate portion of the tower. Thus, there may be relatively slow and progressive movement of the catalyst liquid downwardly through the tower countercurrent to the upwardly rising drops of hydrocarbon, the latter of course moving at a substantially higher velocity than the velocity of movement of the catalyst. In such event, the dispersed hydrocarbon drops are still appropriately described as rising upwardly through a "relatively stationary" body of the catalyst liquid, and this expression is used as a matter of convenience throughout the description and claims to include these various operations as above described.

It is therefore seen that, in accordance with the present invention, the necessity for handling and recycling catalyst, or an emulsion containing catalyst, by high capacity pumps or other moving parts is avoided. The recycle of hydrocarbon unmixed with catalyst can be accomplished without corrosion or erosion difficulties. The tower itself and other parts such as the separator and lines which contact the catalyst can readily be constructed of corrosion-resistant material; and the more highly corrosive catalyst does not come in contact with moving parts, pump packings and the like.

It has heretofore been proposed to effect absorption or polymerization of olefins by dispersing the olefins in liquid phase through nozzles into a body of sulfuric acid. However, it is well recognized that such reactions take place readily without efficient agitation. It has also been proposed to apply this operation to a refinery C4 cut from which isobutylene had been removed, and which contained both isobutane and n-butylanes with the latter in molar excess, in the presence of strong H₂SO₄ of at least 87%, for the absorption of n-butylanes in the acid and the concomitant production of a small yield of gasoline hydrocarbons of an unsaturated character. It has not been heretofore recognized and taught that, in accordance with the method of the present invention, and by avoiding efficient agitation producing an emulsion, alkylation of a hydrocarbon or paraffin with an olefin or other alkylating agent could be accomplished as the principal reaction of the process, with minimum olefin absorption and/or polymerization, whereby a substantially saturated alkylate of good quality is obtained with minimum catalyst deterioration and resultant long catalyst life. This was unexpected and directly contrary to the previous knowledge and experience in this alkylation art. As pointed out above, this invention is particularly advantageous for those alkylation catalysts which are more corrosive to pump parts and packings than sulfuric acid, such as HF, HF-BF₃, BF₃.nH₂O, etc., as well as for those alkylation catalysts which tend to clog emulsion recycle lines, such as the aluminum chloride-hydrocarbon complex containing suspended aluminum chloride.

Obviously many modifications and variations of the invention, as hereinbefore set forth, may be made without departing from the spirit and scope thereof, and therefore only such limitations should be imposed as are indicated in the appended claims.

I claim:

1. The method of continuously alkylating a hydrocarbon having a replaceable hydrogen at-

om with an alkylating agent in the presence of an alkylation catalyst of greater specific gravity than the hydrocarbon and alkylating agent, which comprises maintaining an undispersed liquid body of the alkylation catalyst of substantial height as the continuous phase in a reaction zone, continuously dispersing a fresh feed of mixed hydrocarbon and alkylating agent substantially free from alkylation catalyst and with the hydrocarbon in liquid phase into a lower portion of the liquid catalyst body without dispersion of the latter to form a multitude of fine liquid drops of mixed hydrocarbon and alkylating agent which rise in dispersed form through a substantial height of the continuous catalyst phase due to difference in gravity therebetween, whereby alkylation of the hydrocarbon with the alkylating agent to form normally liquid alkylate takes place as the principal reaction of the process, the dispersed drops coalescing to form a hydrocarbon phase upon reaching the upper surface of the liquid catalyst body, continuously removing a stream containing the coalesced hydrocarbon phase, settling any entrained catalyst from the removed stream to provide a hydrocarbon layer substantially free from catalyst, recycling a major portion of the hydrocarbon layer containing alkylate and substantially free from catalyst and mixing the same with the fresh feed for redis-

portion unmixed with alkylation catalyst into the lower portion of the catalyst body, recovering a substantially saturated hydrocarbon alkylate from a minor portion of said hydrocarbon layer, and adding fresh alkylation catalyst directly to the maintained body without premixing with said fresh feed as the operation proceeds to preserve the alkylating activity thereof.

2. The method according to claim 1, wherein the said hydrocarbon is a low-boiling isoparaffin and the alkylating agent is an olefin, and the liquid catalyst comprises hydrofluoric acid.

3. The method according to claim 1, wherein the said hydrocarbon is a normal paraffin and the alkylating agent is an olefin, and the liquid catalyst consists essentially of a major proportion of substantially anhydrous hydrofluoric acid containing a minor proportion of boron fluoride.

4. The method according to claim 1, wherein the rate of throughput of fresh feed and recycled hydrocarbon produces a dispersion of a large number of drops each of less than $\frac{1}{4}$ inch in diameter throughout the liquid catalyst body giving a substantial rise in the operating level of the interface between the catalyst liquid and the superposed hydrocarbon layer above the initial level of the catalyst body alone, the said rate being below that which causes an accumulation of the fresh feed and recycle liquid immediately about the region of dispersion in the lower portion of the reaction zone resulting in a reduction in the degree of dispersion of the drops and a lowering of the interface level.

5. The method according to claim 1, wherein at least a portion of the settled catalyst is re-
turned directly to the maintained catalyst body without previous mixing with the fresh feed and recycled hydrocarbon dispersed into the lower portion of the catalyst body.

6. The method according to claim 1, wherein the hydrocarbon is a paraffin, and the alkylating agent is an olefin.

7. The method according to claim 1, wherein the movement of the dispersed liquid drops rising through the liquid catalyst body in the reac-
tion zone is modified and increased in length by contact with packing material submerged within

the liquid catalyst body.

8. The method of continuously alkylating a hydrocarbon having a replaceable hydrogen atom with an alkylating agent in the presence of an alkylation catalyst of greater specific gravity than the hydrocarbon and alkylating agent, which comprises maintaining an undispersed liquid body of the alkylation catalyst of substantial height as the continuous phase in a reaction zone, continuously dispersing a fresh feed of mixed hydrocarbon and alkylating agent substantially free from alkylation catalyst and with the hydrocarbon in liquid phase into a lower portion of the liquid catalyst body without dispersion of the latter to form a multitude of fine liquid drops of mixed hydrocarbon and alkylating agent which rise in dispersed form through a substantial height of the continuous catalyst phase due to difference in gravity therebetween, whereby alkylation of the hydrocarbon with the alkylating agent to form normally liquid alkylate takes place as the principal reaction of the process, the dispersed drops coalescing to form a hydrocarbon phase upon reaching the upper surface of the liquid catalyst body, continuously removing from substantially at the level of the interface between the upper surface of the continuous catalyst body and the lower surface of the coalesced hydrocarbons a stream containing coalesced hydrocarbons along with some overflow catalyst liquid, rapidly separating catalyst liquid from the removed stream to provide a hydrocarbon layer substantially free from catalyst, removing a stream of the hydrocarbon layer and recovering a substantially saturated hydrocarbon alkylate therefrom, and adding alkylation catalyst directly to the maintained catalyst body without pre-
mixing with said fresh feed as the operation pro-
ceeds to maintain the volume and alkylating ac-
tivity of the said catalyst body.

9. The method according to claim 8, wherein at least a portion of the settled catalyst together with fresh make-up catalyst is returned directly to the maintained catalyst body without previous mixing with the fresh feed at a level near the lower portion of the maintained catalyst body.

LOUIS A. CLARKE.
